United States Patent Office.

ROBERT ROWAN, OF PARNASSUS, PENNSYLVANIA.

Letters Patent No. 79,399, dated June 30, 1868.

IMPROVED SCAFFOLD AND LADDER.

The Schedule referred to in these Letters Patent and making part of the same.

TO ALL WHOM IT MAY CONCERN:

Be it known that I, ROBERT ROWAN, of Parnassus, in the county of Westmoreland, and State of Pennsylvania, have invented a new and improved Ladder and Scaffold, for painting and other purposes; and I do hereby declare that the following is a full, clear, and exact description thereof, which will enable those skilled in the art to make and use the same, reference being had to the accompanying drawing, forming part of this specification.

This invention relates to an apparatus for facilitating the operation of painting buildings, and which is adapted to other uses where work is to be performed on buildings in elevated situations.

And it consists in a horizontal bar, supported at any desired height from the ground, and in providing it with pulleys at each end, and in a ladder and traversing-frame, arranged in such a manner that the ladder may be moved laterally either way from the middle of the bar, as will be hereinafter more fully described.

The drawing represents an elevation of the apparatus.

A is the bar.

B is the ladder.

C represents the standards by which the bar is supported.

D is the traversing-frame, from which the ladder is suspended.

E E are the traversing-rollers.

There is a round guide-rod or metallic track on top of the bar A, as seen at e, which the rollers are grooved or formed to fit, and by which they are guided as they traverse back and forth.

ff represent stirrups, which are suspended from the frame D, which enclose the bar A, with hooks at their bottom ends, to which the sides of the ladder are attached, as seen in the drawing.

g g are pulleys in these stirrups, which revolve on pivots.

h h are pulleys at the ends of the bar A.

The ladder is made double, or in the form of a square, as seen in the detached view, J, so that one or more scaffolds or platforms may be made on the ladder, from which the mechanic may prosecute his work, as painting or other occupation.

These scaffolds will allow the workman to ascend or descend, as his work may require, but to move himself either way laterally I apply ropes k k to each end of the traversing-frame A.

These ropes extend from the ends of the frame, over the pulleys h h on the ends of the bar A, and over the pulleys g g on the stirrups ff, from which the ends of the ropes hang down within reach of the workman, as seen.

By drawing upon either of the ropes, the traversing-frame D and the ladder or scaffold will be moved to the right or to the left, as may be desired, without moving the workman from his seat or station on the scaffold.

The standards C C will stand in a bracing position, leaning against the building, but the bar A may be supported from windows, or in any other suitable manner.

The ladder may be made single, like ordinary ladders, if desired, but a better and more convenient platform or scaffold is made by having the ladder made double.

The ladder may be made with either flexible or rigid sides, but the flexible sides allow the apparatus to be transported with greater ease, and to be folded away in a small space when not in use.

I claim as new, and desire to secure by Letters Patent—

The bar A and the traversing-frame D, in combination with a ladder or scaffold, when arranged and operated substantially as and for the purposes herein shown and described.

The above specification of my invention signed by me, this 20th day of April, 1868.

ROBERT ROWAN.
